UNITED STATES PATENT OFFICE.

SVEND HANSEN, OF BROOKLYN, NEW YORK, ASSIGNOR TO BIRMINGHAM IRON FOUNDRY, OF DERBY, CONNECTICUT, A CORPORATION.

ROLL-GRINDER.

1,385,077.

Specification of Letters Patent. Patented July 19, 1921.

Application filed March 5, 1919. Serial No. 280,821.

To all whom it may concern:

Be it known that I, SVEND HANSEN, a citizen of the United States, residing at Brooklyn, in the county of Kings and State of New York, have invented a new and useful Improvement in Roll-Grinders; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a grinding machine construction in accordance with my invention.

Fig. 2 a side view of the same.

Fig. 3 an enlarged sectional view of the centering pin for the swinging table.

Fig. 4 a side view of the crowning bar, bearing box and the pivotal block which it moves.

Fig. 5 a sectional view on the line 5—5 of Fig. 4 in connection with the ball-bearing raceways, crowning bar, and showing particularly the connection with the swinging table.

Fig. 6 a plan view of the crowning bar, detached.

Fig. 7 an edge view of the same.

Fig. 8 a plan view of the crowning bar bracket.

Fig. 9 an edge view of the same.

Fig. 10 a plan view of the swinging table yoke.

Fig. 11 a side view of the same.

Fig. 12 a plan view of the swinging table bracket.

Fig. 13 a side view of the same.

Figs. 14, 15 and 16 are diagrammatic views showing the position of the roll with respect to the grinding wheel at extreme points in the operation.

This invention relates to an improvement in roll grinders. It is desirable that rolls for certain purposes, such, for instance, as rolling tinfoil, should have their faces convexed, as in use the rolls being supported at their ends, if perfectly straight, will yield slightly so that the foil will be thicker at the center of the roll than at the sides, whereas if the rolls are slightly crowning or convexed when brought together under pressure, they will yield at the center and compensate for the convexity and produce a

sheet of uniform thickness. Heretofore these rolls have been ground on two tapers or from a templet and an irregularity in the templet will be reproduced on the roll and these irregularities must be finally worked down by hand, requiring a large amount of time and constant gaging.

The object of this invention is to provide a machine by which the surface of rolls may be ground to any desired curvature; and the invention consists in certain details of construction and combination of parts as will be hereinafter described and particularly recited in the claims.

In carrying out my invention I employ a grinding machine of usual construction comprising a bed 20 on which is a sliding carriage 21 on which is adjustably mounted a grinding wheel 22. Fixed in a flange 23 of the machine bed 20 is a pin 24 formed with a round flat head 25 which has a close fit in a ring 26 secured to the underside of a swinging table 27 which is centrally mounted on said head 25 which rests on ball bearings 28 between the under face of the swinging table and the machine bed. Mounted on the swinging table are heads 29 and 30 carrying center points 31 and 32 between which the roll 33 to be cut is mounted, this roll being driven through a belt 34 turning a pulley 35 connected with one of the centering points. Fixed to the carriage 21 and so as to move therewith is a crowning bar bracket 36 formed with a downwardly extending lug 37 which is also bolted to the carriage so as to form a firm connection therewith. At the center of the inner end of the crowning-bar bracket is a boss 38 into the top of which is screwed a pin 39, and mounted on this pin is a straight bar 40 commonly called a crowning bar the outer end 41 of which rests upon a lip 42 between screws 43 and 44 mounted in lugs 45 and 46 in the crowning bar bracket and by which the outer end of the crowning bar may be adjusted.

This crowning bar extends through a bearing box 47. The interior of this box is provided with hardened ball-bearing plates 48 between which and the edges of the crowning bar 40 are ball bearings 49 mounted in raceways 50 and 51 which are considerably longer than the length of the box. At the ends of the raceways are stops 52 to engage with the sides of the box 47. Mounted in the top of the box 110

is a pin 53 over which is set a block 54 which extends between arms 55 and 56 of a yoke 57 which is bolted to the side of a bracket 58 which in turn is bolted to the outer end 5 of the swinging table 57, this block being adjustably connected with the yoke by means of an adjusting screw 59 held by lock-nuts 60 and 61 bearing upon a cross bar 62 in the yoke. The roll 33 to be cut is mounted 10 between the centers 31 and 32 and the outer end of the crowning bar adjusted corresponding to the curvature to be given to the surface of the roll, the diameter of the roll at the center being only a few thousandths 15 of an inch greater than the diameter of the rolls at the ends. The crowning bar being moved in the direction of the arrow 63 to the desired extent that crowning bar may be firmly clamped to the lip 42 by a set screw 20 64. As the carriage 21, carrying the grinding wheel advances, the grinding wheel contacts with the outer end of the roll as indicated in Fig. 14 so as to reduce that end to the desired diameter, and as the grinding 25 advances the crowning bar is pulled through the box 47, gradually crowding the yoke 57 outward, thus gradually swinging the table 27 on its center and gradually moving the roll away from the grinder until it 30 reaches the center, as indicated in Fig. 15 of the drawings. As the grinder advances the axis of the roll continues to turn in the same direction as before until the grinder reaches the other end of the roll, as indicated in 35 Fig. 16 of the drawings, at which time that end of the roll will have been ground away to the same extent as the starting end. In other words, the roll will have been given a true arc the axis of which will correspond 40 to the extent to which the crowning bar has been adjusted. It is apparent, without illustration, that should the crowning bar be adjusted in the opposite direction the roll will be given a convex surface should such 45 a form be desired for any particular purpose. The roll when ground is removed, the carriage reversed in position and another roll mounted between the centers preparatory to grinding, and any number of rolls 50 may be ground and present uniform surfaces. The raceways as shown, are made longer than the box so as to distribute the wear over a number of balls, but in case of a long roll the stops 52 will engage with the 55 side of the box 47 but not interfere with the longitudinal movement of the crowning bar through it.

With the construction shown, the several parts are removable for replacement, and 60 provision is made for adjustment so that perfect accuracy may always be secured. As before stated, the cutting is made to a few thousandths of an inch so that slight variation would make considerable difference in the final result.

I claim:—

1. A roll grinding machine, comprising a sliding carriage carrying a grinding wheel, a centrally mounted swinging table mounted adjacent to the sliding carriage, means 70 for mounting a roll on said swinging table, means for revolving said roll, a crowning bar bracket connected with the sliding carriage, a crowning bar pivoted to the inner end of the crowning bar bracket, and means 75 interposed between the said crowning bar and table to turn the table as the carriage moves.

2. A roll grinding machine, comprising a sliding carriage carrying a grinding wheel, 80 a centrally mounted swinging table mounted adjacent to the sliding carriage, means for mounting a roll on said swinging table, and means for revolving said roll, a crowning bar bracket connected with the sliding carriage, a crowning bar pivoted to the inner end of the crowning bar bracket and adjustably connected with the outer end of the bracket, and means interposed between the 85 said crowning bar and table to turn the table 90 as the carriage moves.

3. A roll grinding machine comprising a sliding carriage carrying a grinding wheel, a swinging table mounted adjacent to the sliding carriage, means for mounting a roll 95 on said swinging table, and means for turning said roll, a crowning bar bracket connected with the sliding carriage, a crowning bar pivoted to the inner end of the crowning bar bracket and adjustably connected with the outer end of the bracket, a box through which the crowning bar extends, a block connected with said box, a yoke connected with the swinging table, and connections between the said block and yoke 100 whereby the sliding movement of the crowning bar imparts a movement to the said swinging table to turn the axis of the roll 105 at an angle to the line of movement of the grinding wheel.

4. A roll grinding machine comprising a sliding carriage carrying a grinding wheel, a swinging table mounted adjacent to the sliding carriage, means for mounting a roll on said swinging table, and means for turning said roll, a crowning bar bracket connected with the sliding carriage, a crowning bar pivoted to the inner end of the crowning bar bracket and adjustably connected with the outer end of the bracket, a box through 115 which the crowning bar extends, ball-bearing raceways between the crowning bar and box, a block connected with said box, a yoke connected with the swinging table, and connections between the said block and yoke 120 whereby the sliding movement of the crowning bar imparts a movement to the said swinging table to turn the axis of the roll at 125 an angle to the line of movement of the grinding wheel.

5. A roll grinding machine comprising a longitudinal movable grinding wheel carriage, a centrally mounted swinging roll carrying table and means including a straight 5 crowning bar interposed between said carriage and table to turn the table on its center as the carriage moves.
6. A roll grinding machine comprising a longitudinal movable grinding wheel carriage, a centrally mounted swinging roll carrying table and adjustable means including a straight crowning bar interposed between said carriage and said table to turn the table on its center as the carriage moves. 10
- 15 7. A roll grinding machine including a traveling-member, a centrally-pivoted member, a straight crowning bar adapted to be turned to an angle with the path of movement of the traveling-member, and a pivotal connection between the crowning bar and 20 centrally-pivoted member, whereby the centrally-pivoted member is turned on its center as the traveling-member moves.

In testimony whereof, I have signed this specification in the presence of two subscribers. 25
